Oliver L. Ayers, Alexandria, Va.

Application September 28, 1955, Serial No. 38,147

Term of patent 14 years

(Cl. D31—4)

Fig. 1.

Fig. 2.

Fig. 3.

Fig. 1 is a side elevational view, partly in section, of a night-fishing reel attachment for flashlights, showing my new design;

Fig. 2 is a perspective view; and,

Fig. 3 is an elevational view of the forward end thereof.

The side opposite that shown in Fig. 1 is the same except that no opening is provided.

The flashlight shown in broken lines in Fig. 1 is for purposes of illustration only.

I claim:

The ornamental design for a night-fishing reel attachment for flashlights, as shown and described.
